UNITED STATES PATENT OFFICE.

JOHN EMEL, SR., OF SILVERDALE, WASHINGTON.

VEGETABLE-SLICER.

1,094,318.

Specification of Letters Patent. Patented Apr. 21, 1914.

Application filed June 27, 1912. Serial No. 706,236.

To all whom it may concern:

Be it known that I, JOHN EMEL, Sr., a citizen of the United States, residing at Silverdale, in the county of Kitsap, State of Washington, have invented certain new and useful Improvements in Vegetable-Slicers; and I do hereby declare the following to be a full, clear, and exact description of the invention, such as will enable others skilled in the art to which it appertains to make and use the same.

This invention relates to improvements in vegetable slicers.

The principal object of the invention is to provide a device of the character described which can be easily supported by one hand of the operator and operated by his other hand.

Another object of the invention is to provide a slicer of the character described which includes a plurality of rotatable knives that operate under a pair of vegetable receiving pockets, the vegetables being pressed downwardly for engagement with the knives by a resilient means of novel construction.

A further object of the invention is to provide a slicing device of the type described which is composed of a minimum number of parts, is therefore simple in construction, and is cheap to manufacture.

With these and other objects in view, the invention consists in the construction and novel combination of parts hereinafter fully described, illustrated in the accompanying drawings and pointed out in the claim hereto appended; it being understood that various changes in the form, proportion, size and minor details of construction within the scope of the claim may be resorted to without departing from the spirit or sacrificing any of the advantages of the invention.

In the drawings: Figure 1 is a top plan view of a slicer constructed in accordance with my invention, Fig. 2 is a side elevation, Fig. 3 is an end view of the same, Fig. 4 is a longitudinal sectional view taken on the line 4—4 of Fig. 1, Fig. 5 is a detail sectional view taken on the line 5—5 of Fig. 1, showing the resilient pressers, and Fig. 6 is a perspective view of the follower frame.

Like reference numerals designate corresponding parts in all the figures of the drawings.

Referring to the drawings, 5 designates a

handle which is formed from a single length 55 of strap metal, and is centrally bent to form a hand-hold 6, the ends of the strap being extended in parallel relation to form supporting arms 7—7, the upper arm terminating short of the bottom arm, and the free 60 end of the bottom arm being bent upwardly and thence inwardly, as at 8, and terminating adjacent the free end of the upper arm. The lower arm at the bend is formed with a central opening 9. An opening is 65 formed adjacent the free end of the upper arm and an alined opening is formed in the lower arm, and mounted for rotation within these openings is a vertical axle 10 which supports at its lower end a horizontally ro- 70 tatable knife-carrying element 11. This element is disposed directly below the lower bar 7 and is circular in contour, and is formed on its upper face with a series of gear teeth 11^a. This element is formed with 75 a plurality of openings 12, and carried by said element and respectively arranged in the rear of said openings is a plurality of radially extending knives 13. Extending from opposite sides of the arm 7 and on 80 either side of the axle 10 is a pair of semi-circular vertically disposed walls 14—14 which constitute pockets for receiving vegetables or other articles to be sliced.

My invention further comprises a fol- 85 lower, which is designated as a whole by the reference numeral 15. This follower is pref- erably formed of spring wire, and is cen- trally bent to form an eye 16 which is se- cured to the upper end of the axle 10. The 90 end portions of this wire extend upwardly and thence downwardly and form an op- posed pair of inverted U-shaped arms, each arm being indicated as a whole by the refer- ence numeral 17. The free ends of the arms 95 are respectively disposed within the pockets above mentioned and carry follower heads 18. These arms which, as above noted, are formed of spring metal, are employed for urging large fruits of greater diameter than 100 the height of the pockets downwardly for engagement with the knives as said knives are rotated therebelow.

In order to rotate the knife-carrying ele- 105 ment, a longitudinally disposed axle 20 pro- jects through the opening 9 formed in the lower arm 7. The inner end of this axle is bent around the vertical axle 10 and the

outer end of this axle projects above the gear teeth 11^a of said element 11. A pinion 22 is loosely mounted upon the projecting end of the last mentioned axle, and associated therewith is a crank 23.

From the foregoing, it will be observed that after vegetables or the like have been positioned within the pockets, the follower heads will be caused to yieldingly bear thereupon and cause said vegetables to be depressed for engagement with the knives. The crank handle 23 is rotated, and through the medium of the pinion 22 the knife-carrying element is rotated. As a result, the knives passing below the vegetables will slice the same and these slices will readily pass into the openings of the element from whence they can drop into any convenient receptacle intended to receive them.

What is claimed is:

The combination with a handle, of spaced frame members extending from said handle, a pivot pin projecting through said frame members, a shaft carried by said pivot pin between said frame members and extending laterally from the pin, a cutter carrying wheel pivotally mounted on said pivot pin, driving means for said wheel mounted on said shaft, and a follower supporting arm carried by said pin, whereby said pin connects the frame, the wheel, the shaft and the follower arm.

In testimony whereof I affix my signature in presence of two witnesses.

JOHN EMEL, SR.
